UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS.

SEPARATOR.

Application filed February 19, 1925. Serial No. 10,163.

The invention to be hereinafter described relates to separators for grading materials.

One of the purposes of the invention is to provide simple and efficient means for vibrating and tensioning a screen. To accomplish this, in the present instance, the screen is suspended between an eccentric vibrating mechanism and spring means. The eccentric preferably has slight eccentricity and is rotated at high speed. The construction is such that the eccentric moves the screen in one direction and allows the spring means to move the screen in the opposite direction. Since the eccentric does not have the work of shaking the screen in opposite directions, the wear thereon is reduced. The spring means holds the strap or follower of the eccentric thereto, so that lost motion is eliminated and wear is further reduced. The eccentric and the spring means desirably cooperate in imparting reciprocatory movements to the screen with high frequency.

The screen may be in the form of woven screen clothing having opposed edges secured to spreader bars or members. The eccentric mechanism may be connected to one of said members and the spring means may be connected to the other member, the construction being such that the spring means will tension the screen clothing and maintain the same in taut condition.

These separators usually operate in dusty atmosphere, and therefore it is important that the eccentric mechanism shall be protected. Another purpose of the invention is to provide effective means for preventing dust from reaching the bearings and other parts of the eccentric mechanism, and at the same time provide for the necessary lubrication thereof.

With the aforesaid and other purposes in view, the character of the invention may be best understood by reference to the following description of an illustrative embodiment of the invention shown in the accompanying drawings, wherein:

Fig. 1 is a plan of a separator embodying the invention;

Fig. 2 is a vertical section taken on line 2—2 of Fig. 1;

Fig. 3 is a perspective view of an end portion of the screen;

Fig. 4 is a vertical section on an enlarged scale through the eccentric mechanism;

Fig. 5 is a vertical transverse section taken 55 on line 5—5 of Fig. 4;

Fig. 6 is a sectional detail taken on line 6—6 of Fig. 4;

Figs. 7 and 8 are respectively a plan and a side elevation of a pair of screens and connections therefor, and

Fig. 9 is a detail to be referred to.

Referring to the drawings, the separator shown therein as an illustrative embodiment of the invention, may have a suitable support, in the present instance, in the form of a frame comprising side channels 1 (Figs. 1 and 2) connected by end channels 3 and 5 adjacent opposite ends of the side channels. To contribute to the stiffness of the frame, the side channels may be connected by angle bars 7 and 9. Secured to the end channel 3 is an angle bar 11 having a pair of ears 13 depending therefrom and connected by a shaft 15 with a pair of feet 17. The ears constitute a rocker enabling the angle of the frame to be varied as more fully hereinafter described. At the opposite end of the frame from the rocker and secured to the side channels are a pair of eyes 19 through which extend a pair of threaded posts 21 having heads mounted on feet 23. Nuts 25 are threaded on the posts at opposite sides of the eyes 19. The construction is such that the nuts may be adjusted thereby to rock the frame on the shaft 15 to different elevations to give the frame the degree of inclination desired. The heads of the threaded posts have curved slots therein cooperating with the feet 23 to allow rocking of the posts on the feet. The frame may be adjusted so that it inclines downward or upward toward the right of Fig. 2.

Supported on the frame is a screen, in the present instance, comprising woven wire screen clothing 27 having opposite edge portions thereof entered between and secured to pairs of bars or members 29 and 31. The bars have upstanding end portions 33 and 35, and the clothing has upstanding side portions 37 terminating in selvage edges 39. Said upstanding side portions of the clothing serving to prevent materials from escaping over the edges of the screen.

The bars 29 at one end of the screen are connected to ends of rods 41 which extend through holes in the end channel 3 of the frame and have portions extending a substantial distance beyond said channel. Encircling these portions of the rods are coil springs 43 confined between the channel and adjusting nuts 45 threaded on the rods and secured by lock nuts 47.

10 The eccentric mechanism referred to, is mounted on the end channel 5 of the frame, and comprises a casing 49 (Figs. 1, 2, 4 and 5) secured to said channel by bolts 51. The casing is formed of a lower part 53 and an upper part 55 which are secured together by bolts 57. One side of the casing has an opening which is normally closed by a door 59 pivoted on a screw bolt 61, said door being provided with a handle 63. This door may 15 be readily swung about the screw bolt 61 to open the same, and will naturally gravitate to and remain in its closed position.

At opposite ends of the casing are apertures 65 and 67 adapted to receive boxes 69 and 71 confined against axial movement by dowel pins 73. Mounted in these boxes are Timken roller bearings, each comprising an outer raceway 75, an inner raceway 77, and rollers 79. The inner raceways are mounted fast on the reduced ends of the shaft 81 which is extended beyond one end of the casing, where it receives a pulley 83 adapted to be belted to any convenient source of power. The box 69 has a boss 85 projecting therefrom grooved to receive suitable packing 87. The inner sides of the boxes are closed by rings 89 apertured to receive the shaft, and secured in the boxes by set screws 91. These rings are grooved to receive suitable packing 93. The outer side of the box 71 is closed by a cover 95 having a flange 97 for engagement with the outer raceway 75 of said box. Screw bolts 99 are entered into the cover and the box, and enable adjustment thereof to take up any wear between the rollers and raceways of the Timken bearings. These bearings may be lubricated by the well known Alemite system. To permit this, the box 69 is provided with a lubricating neck 101, and the cover 95 for the box 71 is provided with a lubricating neck 103.

55 Mounted on the shaft 81 between the boxes 69 and 71, is an eccentric sleeve 105, and encircling said sleeve are a pair of rings 107 which are eccentric in form and so disposed with respect to the sleeve as to counterbalance the same. Screw bolts 109 are threaded into the thickest portions of these rings and entered through the sleeve into the shaft and serve to lock the sleeve and rings to the shaft.

60 A cylindrical box 111 is mounted on the sleeve, and has a head 113 and a cover 115 through which the shaft extends. The head and cover are grooved to receive suitable

packing 117 and 119. The cover has a flange 121 which is threaded to the body of the box, said cover being secured in different positions of adjustment by screws 123 which are threaded into the cover and have pointed heads 125 for engagement with dents in a flange 127 projecting outward from the box and forming one side of a circumferential groove 129 to be referred to.

65 Mounted in the box 111 are a pair of Timken roller bearings, each comprising outer raceways 131 fitted into the box, inner raceways 133 on the eccentric sleeve, and rollers 135 between the outer and inner raceways. A circumferential flange 137 projects outward from the eccentric sleeve, and is engaged by adjacent ends of the inner raceways, and thereby holds the same in proper spaced relation. The Timken bearings in the box may be lubricated by the Alemite system, said box being provided with lubricant conducting necks 139 for this purpose.

70 A strap 141 partially embraces the groove 129 referred to on the box 111, and the portions of said strap extend through openings 143 (Fig. 5) in converging relation, the ends of the strap being connected by a bolt 145 (Figs. 1, 2 and 3) with a bridle 147 (Fig. 1) comprising pairs of links 149 secured to the screen end bars 31 referred to.

75 From the above description it will be apparent that the screen is suspended between the eccentric mechanism and the springs. To contribute to the support of the screen, pairs of rollers 151 and 153 may be mounted on shafts 155 and 157 secured in the side channels of the frame, said rollers being located beneath the end bars 33 and 35. An inclined plate 159 may be secured to the end bars 33, and serve to guide materials flowing from the screen. Materials may be guided to the screen by a chute 161 (Fig. 2) mounted on uprights 163 and 165 carried by the frame.

80 The eccentric preferably has slight eccentricity, and is rotated at high speed. Since the eccentric strap 141 only partially embraces the eccentric box 111, the eccentric will shift the strap and the screen connected thereto intermittently toward the left (Figs. 1 and 2), and the springs 43 will operate through the rods 41 intermittently to shift the screen toward the right of said figures. The springs are adjusted so that they will maintain the screen clothing in proper stretched condition. Since the eccentric is not called upon to perform the work of shaking the screen in opposite directions, the wear thereon is reduced, and since the springs always tend to draw the strap in one direction, there is no lost motion between the parts of the eccentric mechanism, and the wear thereon is further reduced.

85 The eccentric and its strap at one end of the screen, and the springs and their rods

at the opposite end thereof serve not only to cooperate in shaking the screen, but also to support the same. Under certain conditions the rollers 151 and 153 may be relied upon to contribute to the support of the screen. The angle of the screen may be varied by adjustment of the nuts 25 along the threaded posts. If the angle of the screen is slight, a substantial mass of material being graded 10 may stand on and be supported by the screen. This may deaden vibration of the screen transversely to the plane thereof, but it will not interfere with the vibration of the screen in the direction of the plane there- 15 of since the eccentric and springs operate positively to reciprocate the screen. In a sense the screen may be regarded as grating or sawing material from the mass of material upon it. When a small amount of material 20 is upon the screen it may have trans- verse vibrations in addition to its longitudinal vibrations.

The parts of the eccentric mechanism may be easily and quickly assembled. To accomplish this the journal boxes 69 and 71 and the eccentric box 111 are mounted on the eccentric shaft 81 and the journal boxes are placed in the lower part 53 of the casing 49 in proper registration with the dowel pins 73. Then the upper part 55 of the casing is mounted on and bolted to the lower part of the casing.

The journal boxes are closed and protected from ingress of dust therein. The eccentric box is closed and protects the eccentric and parts associated therewith from ingress of dust. Also further protection is had by the closed casing 49.

The boxes may be filled with grease to insure proper protection of the Timken roller bearings. Wear on the bearings of the journal boxes 69 and 71 may be taken up by adjustment of the cover 95 of the box 71 and wear on the bearings in the eccentric box may be taken up by adjustment of the cover 115 of said box.

In Figs. 7 and 8 are shown an upper or scalper screen 167 and a lower or fine screen 169. These screens are connected by stirrups 171 suitably secured to end bars of the screens and adapted to be connected by links 173 with the eccentric strap 141 referred to, and the screens are connected by stirrups 175 suitably secured to the opposite end bars of the screens and adapted to be connected to the spring rods 41 referred to. The eccentric and springs will cooperate to shake the pair of screens with minute amplitude and high frequency of reciprocations as already described in respect to the single screen. The links 173, in the present instance are connected to the stirrups 171 at points which are intermediate the upper and lower ends of the stirrups and the planes of the screens, 65 and the rods 141 are connected to the stir-

rups 175 at points intermediate the outer ends of the stirrups and the planes of the screens. The construction is such that the tension on the upper and lower screens is desirably proportioned.

Under certain conditions it may be desirable that the screen shall receive vibration positively transversely to the plane thereof. To accomplish this devices may be substituted for the rollers 151 and 153 referred to. In the present instance each of these devices comprises a link or toggle 177 (Figs. 8 and 9) having eyes at opposite ends thereof connected by pins 179 with brackets 181 and 183, one secured to an end bar of the screen and the other secured to one of the frame angle bars beneath the screen. These toggles may stand in oblique positions when the screen is shifted to the right by the springs and in erect positions when the screen is shifted to the left by the eccentric. The rocking of these toggles, caused by the reciprocation of the screen by the eccentric and springs, will positively impart to the screen vibration transversely to the plane thereof. While these toggles are shown applied to the pair of screens, it will be understood they may be applied to a single screen.

It will be understood that the invention is not limited to the construction shown in the drawings and that various deviations may be made therefrom without departing from the spirit and scope of the appended claims.

What is claimed is:

1. A separator for grading materials comprising, in combination, an eccentric of slight eccentricity, spring means, and screen clothing between and connected to the eccentric and spring means, said screen clothing being maintained in taut condition by said eccentric and spring means, and said screen clothing being vibrated in the plane thereof by cooperative action of said eccentric and spring means.

2. A separator for grading materials comprising, in combination, screen clothing, a pair of separate bars secured to opposed edges of the screen clothing, and an eccentric mechanism and spring means connected to said bars, said eccentric mechanism and spring means cooperating to vibrate the screen clothing and pull said bars in opposite directions to maintain the screen clothing in taut condition.

3. A separator for grading materials comprising, in combination, screen clothing having opposed free edges, and means for stretching and vibrating the screen clothing in the plane thereof including means for positively imparting movements to the screen clothing in one direction in said plane, and spring means for imparting movements to the screen clothing in the opposite direction in said plane, said screen clothing being con-

nected to and receiving support from the means for positively imparting movements thereto.

4. A separator for grading materials comprising, in combination, screen clothing, an eccentric mechanism and spring means located at opposite ends of and connected to edges of the screen clothing, said eccentric mechanism and spring means having provision for imparting a rapid succession of minute vibratory movements to the screen clothing in the plane thereof.

5. A separator for grading materials comprising, in combination, screen clothing having opposed free edges, stiffening members secured to other opposed edges of the screen clothing, an eccentric mechanism including an eccentric having a strap connected to one of said members, and spring means connected to the other member for holding the strap to the eccentric and maintaining the screen clothing in taut condition.

6. A separator for grading materials comprising, in combination, screen clothing having opposed free edges and stiffening members secured to other opposed edges of the clothing, an eccentric mechanism including an eccentric and a strap on the eccentric connected to one of said members, a pair of rods connected to the other member, and coil springs acting on said rods to maintain the screen clothing in taut condition and to hold the strap to the eccentric, said screen clothing and members being supported by the eccentric, its strap, and the rods and their springs.

7. A separator for grading materials comprising, in combination, a supporting frame, a casing mounted thereon provided with bearings, a shaft journalled in said bearings, an eccentric of slight eccentricity on said shaft and in said casing, spring means mounted on said frame, screen clothing between the casing and spring means and free from said frame, means connecting one end of the screen clothing to the eccentric, and means connecting the opposite end of the screen clothing to the spring means.

8. A separator for grading materials comprising, in combination, upper and lower sheets of unframed screen clothing, means to hold them in spaced relation, and means for vibrating said sheets in the planes thereof including an eccentric for positively imparting movements to said sheets in one direction, and spring means for imparting movements to said sheets in the opposite direction in said planes, said upper and lower sheets of screen clothing being stretched by and between said eccentric and spring means.

9. A separator for grading materials comprising, in combination, a frame, an eccentric mechanism mounted on said frame, spring means mounted on said frame, and

unframed screen clothing connected to and vibrated by said eccentric mechanism and spring means, and maintained by the eccentric mechanism and spring means in taut condition.

10. A separator for grading materials comprising, in combination, a support, unframed screen clothing thereon, a casing mounted on the support, a shaft journalled in bearings in the casing, an eccentric on said shaft, a strap on the eccentric and projecting out of said casing and connected to one end of said screen clothing, and spring means on the support and connected to the opposite end of the screen clothing for holding the strap to the eccentric and tensioning the screen clothing, the latter being suspended between the eccentric strap and the spring means.

11. A separator for grading materials comprising, in combination, a casing provided with boxes having bearings therein, a shaft journalled in said bearings, means accessible externally of said casing for adjusting said bearings to compensate for wear thereon, an eccentric on said shaft and within said casing, a screen connected to said strap and spring means operating through the screen to tension the screen and hold the strap to the eccentric, said screen being suspended between the eccentric and spring means.

12. A separator for grading materials comprising, in combination, a shaft having an eccentric thereon, a box on the shaft enclosing the eccentric, bearings having raceways on the box and eccentric respectively and rotative elements between said raceways, said box having a cover adjustable to compensate for wear on said bearings, a strap on the box, a screen connected to said strap, and spring means operating through the screen to tension the screen and hold the strap to the eccentric, said screen being suspended between the eccentric and spring means.

13. A separator for grading materials comprising, in combination, a frame, a screen carried by the frame, toggles connected to the frame and screen, and means for shaking the screen in the plane thereof including an eccentric and spring means connected to opposite edges of the screen, said screen being stretched by and between said eccentric and spring means and said toggles being operable to vibrate the screen transversely to the plane thereof when the screen is shaken by the eccentric and spring means.

14. A separator for grading materials comprising, in combination, a support, unframed screen clothing, means including an eccentric and spring means for shaking the screen clothing in the direction of the plane thereof, said screen clothing being stretched by and between said eccentric and spring

means, and means operable positively to vibrate the screen clothing transversely to the plane thereof when the screen clothing is shaken in the direction of the plane thereof.

15. A separator for grading material, comprising, in combination, a screen, an eccentric and spring means connected to opposite edges of the screen and cooperating to shake the screen in the plane thereof, said screen being stretched by and between said eccentric and spring means, and means operated by such shaking of the screen for vibrating the latter transversely to the plane thereof.

16. A separator for grading materials, comprising, in combination, upper and lower unframed screens and means for tensioning said screens and for vibrating said screens substantially in the directions of the planes

thereof including an eccentric and spring means, and means connecting the eccentric and spring means to opposite ends of the screens, said connecting means having provision for proportioning the tension on the upper and lower screens.

17. A separator for grading materials, comprising, in combination, upper and lower unframed screens, means for tensioning and vibrating said screens including members connecting the upper and lower screens, spring means connected to one of said members, and an eccentric connected to the other member, said spring means and eccentric being connected to said members at points intermediate the planes of the screens, thereby to proportion the tension on the upper and lower screens.

THOMAS J. STURTEVANT.
